UNITED STATES PATENT OFFICE

2,332,605

FILING APPARATUS

Richard P. Scholfield, New York, N. Y., assignor to Scholfield Service, Inc., New York, N. Y., a corporation of New York

Original application April 1, 1941, Serial No. 386,326. Divided and this application August 26, 1942, Serial No. 456,251.

8 Claims. (Cl. 129—16)

The present invention relates to filing apparatus of the type wherein a plurality of cards are secured upon the periphery of a rotatable filing drum, to facilitate access to a great plurality of cards by an operator. The invention includes modification of, improvements upon, and additions to filing apparatus of the type shown in the prior patent to Scholfield et al. No. 2,046,655, July 7, 1936 and in my application Serial No. 75,883, filed April 22, 1936, now Patent No. 2,231,029. This application is a division of my application Serial No. 386,326 filed April 1, 1941, since matured into Patent No. 2,316,489 dated April 13, 1943.

An object of the present invention is to provide improved card retaining rail structures, adapted to perform certain new and improved functions.

A further object of the invention is to provide improved card retaining means whereby a plurality of cards may be removed simultaneously or en bloc from the periphery of the drum.

A further object of the invention is to provide improved card rail shapes and cards having novel slots therein adapted to cooperate with the rails, to secure the cards thereon in an improved manner.

With filing drums of the type shown in the aforementioned patents, the cards are placed upon the card retaining rails by flexing the material of the card adjacent the keyhole-shaped slots therein, thereby effectively but temporarily widening the opening at the narrow throats of the slots and permitting them to move over the rail heads. For a great many uses, drums and cards of that type are entirely satisfactory, but in some cases, it is desirable to remove, from a drum, a relatively great plurality of cards simultaneously, as a group. The present invention provides a construction wherein the cards may be readily removed from the drum periphery by radial movement.

A preferred embodiment of the invention is shown in the accompanying drawings, but it must be understood that the invention is not limited to the specific details of construction shown therein and described below, as many modifications will readily occur to one skilled in the art, from a consideration of the disclosure of this specification.

In the drawings:

Figure 1 is an elevation and partial section of one form of filing drum.

Figure 2 is a transverse, radial section of the upper half of the drum of Figure 1.

Figures 3 and 4 are enlarged sectional views of a movable card retaining member in its two positions.

Figure 5 is a view similar to Figure 4, with one of the cards in a different position.

The filing drum shown in Figure 1 comprises a pair of drum heads 10, 11, which may be formed of stamped or spun metal, and a cylindrical rim 12, preferably constructed of cast aluminum, suitably machined, and secured upon shouldered portions 13, 14 of the drum heads by tie-bolts 15 which draw the heads together and firmly clamp the rim 12 in place. Anti-friction bearings, not shown, are carried by the drum heads 10 and are journalled upon a stationary shaft 16, as is more fully described in the aforementioned Patent 2,231,029. As disclosed in said patent and in Patent 2,046,655, one-way brake means, not shown, may be interposed between the drum and the stationary shaft. The ends of the shaft may be supported in blocks 17, 18, carried by any suitable form of support or cabinet, for instance, of any one of the types shown in the above patents or in my prior Patent 2,205,932, June 25, 1940.

The rim 12 is provided with an integral, outwardly projecting card retaining rail 20, which is accurately machined to the desired cross-sectional shape, preferably as shown in Patent 2,231,029, Figures 5 and 6. In that patent, a continuous rail is disclosed, but, in accordance with the present invention, the rail is interrupted, for instance, at four spaced points around the circumference of the drum, where the rim is apertured as at 21. The inner surface of the rim adjacent the ends of the openings, is provided with downwardly projecting lugs 22 which are socketed to receive pintles 23, 24 of a pivoted member 25 having two webs projecting radially in right angular relation from the axis of the pintles. One web 26 has the same cross-sectional shape as the rail 20 and includes a headed portion 27, at the outer edge of the web. The other web 28 is plane-sided and terminates at its outer edge in a free, non-headed end 29.

Appropriate means, such as a spring-pressed latch 30 (Fig. 2) is provided, to hold the member 25 in either of its two positions, as shown in Figures 3 and 4, respectively.

When the pivoted member 25 is in the position shown in Figures 1, 2 and 4, the head 27 constitutes a continuation of the fixed rail 20 and, therefore, the card retaining rail is continuous around the entire circumference of the drum. If the member 25 is swung to the other position, as shown in Figure 3, however, the non-

headed web 28 is aligned with the fixed card retaining rail. When cards are moved onto this rail section, they may be removed therefrom by radial movement, en bloc, since no head 27 is disposed within the keyhole-shaped openings 31 of the cards.

If desired, the outer edge 29 of the web may be of increasing height, from end to end, so that, as the cards are moved circumferentially onto that web, the edge 29 will engage the inner edges of the keyhole slots 31 and project the cards outwardly beyond the adjacent cards on the fixed rail section, thereby facilitating removal of the cards from the drum.

In this form of the invention, both the fixed card retaining rail section and the movable card retaining rail section have their heads 27 constructed in accordance with the disclosure of my prior Patent 2,281,029, whereby the circular apertures in the cards make a line contact with the rail head, as shown in Figures 4 and 5 and as described in the aforesaid patent.

It will thus be seen that, in accordance with the present invention, a plane-sided, non-headed rail section may be aligned with a fixed rail section, so that cards moved from the latter onto the former, may be removed therefrom en bloc by radial movement relative to the non-headed section.

The filing drum of the present invention may be used in conventional manner, in accordance with the disclosures of the patents mentioned above. However, if it is desired to remove a plurality of cards simultaneously from the drum, or to place a relatively large group of cards thereon at the same time, it is simply necessary to swing the headed rail section laterally to a position below the drum periphery thereby bringing the non-headed section 28 into alignment with the fixed headed section. Cards may then be placed upon or removed from the non-headed section by radial movement.

As stated above, the invention is not limited to the specific details of construction shown in the accompanying drawings and described above, but includes all modifications coming within the scope of the appended claims and their equivalents.

I claim:

1. A rotary filing drum comprising a substantially cylindrical rim and headed card retaining rail means associated with said rim, said rail means comprising fixed and movable sections normally aligned in end to end relation and constituting a substantially continuous circumferential rail, the movable section being pivoted for lateral swinging movement from the normal card retaining position to a card removing position, where said pivoted rail section is disposed radially inwardly of the outer surface of the rim and out of alignment with the cards.

2. A rotary filing drum comprising a cylindrical rim and card retaining rail means associated with the rim, said rail means comprising a plurality of fixed, circumferentially aligned, spaced, headed rail sections and movably mounted sections aligned therewith and interposed therebetween, said rim having openings adjacent the movable rail sections, and pivoted supporting means for the movable sections, whereby they may be swung laterally into said openings and out of alignment with the cards, to permit removal of cards en bloc.

3. A rotary filing drum comprising a cylindrical rim having an opening in its circumference, 75

an outwardly projecting, fixed, headed card retaining rail terminating adjacent the opening, and a movable, headed, card retaining rail having its ends pivoted in the ends of said opening and movable from a card retaining position in alignment with the fixed rail to an inoperative position in the opening, below the rim and out of alignment with the cards.

4. A rotary filing drum comprising a substantially cylindrical rim, a card retaining rail comprising a headed web projecting outwardly from the rim, and means associated with the rail adapted to facilitate removal of a plurality of cards therefrom en bloc, comprising a movably mounted member having a headed web, adapted in one position to constitute a continuation of the rail, and a plane-sided web adapted in another position of the member to be aligned with the rail web, whereby cards moved circumferentially of the drum onto the plane-sided web may be radially removed therefrom en bloc.

5. A rotary filing drum comprising a substantially cylindrical rim, a card retaining rail projecting outwardly therefrom, and means associated with the rail adapted to facilitate removal of a plurality of cards therefrom en bloc, said rail comprising a web connected to the rim and a head at the outer end of the web, said last-mentioned means comprising a movably mounted member having a web and head adapted in one position to constitute a continuation of the rail web and head, said member having a plane-sided, non-headed web portion, adapted in the other position to be aligned with the rail web and being of increasing height from end to end and projecting outwardly beyond the adjacent rail head at one end, whereby cards moved circumferentially of the drum onto said portion are projected outwardly beyond adjacent cards on the rail and may be removed therefrom by radial movement.

6. A rotary filing drum having a cylindrical rim and a headed rail projected outwardly therefrom adapted to retain cards having keyhole slots therein, and means associated with said rail adapted in one position to facilitate removal of cards en bloc and in another position to retain the cards thereon, said means comprising a member pivoted for lateral swinging movement with respect to the rail and having a headed section constituting, in one position, a continuation of the rail, said member also having a straight-sided, non-headed web adapted, in the other position, to constitute a continuation of the rail from which the cards may be removed by radial movement.

7. A rotary filing drum comprising drum heads, a cylindrical rim carried thereby having an opening in its circumference, an outwardly projecting, fixed, headed card retaining rail terminating adjacent the opening, and a member having its ends pivoted in the rim at the ends of the opening, said member having a pair of webs projecting outwardly in right angular relation from the pivotal axis, one of said webs having a headed end adapted to be aligned in one position with the fixed rail and constituting, in that position, a continuation thereof, the other web being plane-sided and unobstructed at its outer edge, whereby, when it is aligned with the fixed rail, cards may be moved thereon by circumferential movement and removed therefrom en bloc by radial movement.

8. A rotary filing drum comprising drum heads, a cylindrical rim carried thereby having an open-

ing in its circumference, an outwardly projecting, fixed, headed card retaining rail terminating adjacent the opening, and a member having its ends pivoted in the rim at the ends of the opening, said member having a pair of webs projecting outwardly in right angular relation from the pivotal axis, one of said webs having a headed end adapted to be aligned in one position with the fixed rail and constituting, in that position, a continuation thereof, the other web being 10

plane-sided and unobstructed at its outer edge, and increasing in height from end to end and projecting outwardly beyond the adjacent fixed rail at one end when aligned therewith, whereby cards moved thereon by circumferential movement project radially outwardly beyond the cards on the fixed rail and may be removed therefrom en bloc by radial movement.

RICHARD P. SCHOLFIELD
